SCRUBBING BRUSH

Harry A. Dorn, Sr., South Bend, Ind.

Application October 19, 1933, Serial No. 694,301

4 Claims. (Cl. 15—122)

The invention relates to scrubbing brushes for cleaning toilet bowls or stools, bathtubs, wash-basins, and the like as well as for general scrubbing purposes, and may also be used for washing dishes, cleaning automobiles, and as a personal bathbrush, and has for its principal object the provision of an improved means for holding the a bar of soap or disinfectant to mix with the water during the scrubbing operation.

10 A further object of the invention is the provision of a brush of the character stated that is extremely simple in construction, is reasonable in cost of manufacture, and that is thoroughly efficient in operation.

15 The construction and advantages of the invention will be more clearly brought out hereinafter and the device will be found illustrated in the accompanying drawing, in which

Figure 1 is a plan view of the brush made in accordance with the invention,

20 Figure 2 is a side view showing the brush in section and the soap container in position in the brush head,

Figure 3 is a side view in elevation of the soap or disinfectant container,

25 Figure 4 is a side view of a bar of soap or disinfectant to be used in connection with the soap container, and

Figure 5 is a transverse sectional view on a plane indicated by the line 5—5 of Figure 3, the parts being shown on an enlarged scale.

In the drawing similar reference characters are used to designate corresponding parts throughout the several views.

30 The improved scrubbing brush includes a handle 10 on which is mounted a brush head 11 having a twisted wire foundation 12 formed into a loop as shown in Figure 1, the ends of said twisted wire foundation being secured in the handle 10 in any suitable manner.

35 Secured to the two sides of the loop of twisted wire 12 is a bar 13, that is arranged adjacent to the handle 10, and on which is mounted a cylindrical container 14 formed of a length of wire 14, and designated 15 may be held by the resilience of the container in the loop comprising the brush head by means of securing said container in said loop and when the coiled wire container is stretched spaces are provided between the adjacent coils for passage of water through the container to dissolve the soap or disinfectant therein. The container is secured

5 to the brush head by means of a loop 16 pivotally engaging the cross bar 13 at one end and the opposite end of the container is provided with a hook 17 that engages the wire loop foundation 12 remote from the handle 10.

10 It will be apparent that any suitable resilient wire may be used for forming the container, but to prevent scratching or abrading the article that is to be cleaned with the brush it is preferred that the wire used for forming the container shall be what is known as insulated wire, having a casing 14a enclosing the wire 14, as shown in Figure 5.

15 It will also be apparent that the soap or disinfectant that may be placed in the container may be of any desired character, but for the most efficient operation of the brush the soap or disinfectant should be manufactured for use in the container in the shape of a bar 18, as illustrated in Figure 4.

20 In use it will be apparent that with the soap or disinfectant within the container 15 the brush may be used in the ordinary way for scrubbing, and that water by contacting with the soap or disinfectant during the scrubbing operation obviates the necessity of applying the soap or disinfectant to the brush bristles.

25 What I claim is:—

1. In combination with a brush having a handle and a loop foundation for brush bristles, 30 a container for soap, disinfectant and the like pivotally secured to said loop foundation, means to removably secure the container to the loop foundation remote from the position where pivotally secured as aforesaid, and the container 35 being porous for the purpose stated.

2. In combination with a brush having a handle and a loop foundation for brush bristles, a cylindrical container for soap, disinfectant and the like pivotally secured to said loop foundation 40 adjacent to said handle, means to removably secure the container to the loop foundation remote from the handle, and the container being porous for the purpose stated.

3. In combination with a brush having a 45 handle and a loop foundation for brush bristles, a container comprising coiled wire for holding soap, disinfectant and the like, one end of said wire being pivotally secured to the loop foundation adjacent to the handle, the other end of said wire being extended from the coil and having its extremity returned on itself to provide a hook engaging said loop foundation remote from the handle, the spaces between the coils 50 of the wire providing means for passage of water 55

into the container to dissolve the contents thereof.

4. In combination with a brush having a handle and a loop foundation for brush bristles, a bar connecting the sides of said loop foundation adjacent to the handle, a length of wire coiled to provide a cylindrical container, one end of said wire provided with an eye pivotally

mounted on said bar, a hook on the other extremity of said wire engaging the loop foundation remote from the handle, the container being adapted to hold soap, disinfectant and the like and the coils being stretched apart to provide spaces for passage of water therethrough.
